CLAIM

The ornamental design for a laser rangefinder, as shown and described.

DESCRIPTION

FIG. 1 is a front elevational view of a laser rangefinder showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, bottom and left side perspective view thereof;

FIG. 8 is a rear, top and right side perspective view thereof; and,

FIG. 9 is an enlarged view of portion 9 in FIG. 7.

The evenly spaced broken lines in the drawings illustrate portions of the laser rangefinder which form no part of the claimed design.

1 Claim, 8 Drawing Sheets
